AUTOMOBILE LAMP LENS HOUSING

Richard G. Macadam, Birmingham, Mich., assignor to Chrysler Corporation, Highland Park, Mich., a corporation of Delaware

Filed May 23, 1960, Ser. No. 60,681

Term of patent 7 years

(Cl. D48—32)

Fig. 1 is a front elevational view of an automobile lamp lens housing, showing my new design;

Fig. 2 is a side elevational view thereof; and

Figs. 3, 4 and 5 are sectional views taken on the lines 3—3, 4—4 and 5—5, respectively, of Fig. 1.

I claim:

The ornamental design for an automobile lamp lens housing, substantially as shown.
